UNITED STATES PATENT OFFICE.

HUGH W. MATTHEWS, OF BALTIMORE, MARYLAND.

THRASHING-MACHINE.

SPECIFICATION forming part of Letters Patent No. 259,185, dated June 6, 1882.

Application filed September 27, 1881. (No model.)

To all whom it may concern:

Be it known that I, HUGH W. MATTHEWS, a citizen of the United States of America, residing at Baltimore, in the county of Baltimore and State of Maryland, have invented certain new and useful Improvements in Thrashing-Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to improvements in thrashing-machines, and has for its object the more perfect and certain separation of the grain from the straw and chaff.

The subject-matter constituting the invention will first be described and its mode of operation explained, and then designated in the claim.

Figure 1 is a side elevation of my improved thrasher, showing the arrangement of the pulleys to effect their relative speed, also the belts for operating the same. Fig. 2 is a vertical longitudinal section of the same, showing the internal arrangement of the carriers and separating-rakes. Fig. 3 is a view of the crank-shaft. Fig. 4 is a top view of the gang-separators. Fig. 5 is a top view of the upper belt or straw-conveyer, showing the grate at the end nearest the concave.

The letter A designates the outer frame or casing of machine, supporting the various journals and bearings for the shafts, and having the openings for the entrance and exit of the straw, grain, and chaff.

B designates the thrashing-cylinder; B', its journals, and B² the concave below the cylinder.

C designates the main shaft, which is a crank-shaft carrying the first gang of straw-separating rollers, and from which the secondary shafts D, E, and F are driven.

D and D' designate the shafts carrying the upper open straw-belt for conveying the straw after it leaves the thrashing-cylinder to the gang-separators.

50 The open straw-belt consists of two belts, a, which are connected by cross-bars b. An in-

clined bottom, c, is provided, over the top of which the cross-bars are passed. At the lower end the inclined bottom has slots d formed in it, constituting a grate which is adjacent to 55 the edge of the concave. The grain and chaff pass down through these slots, and the cross-bars moving over the slots serve to keep them from being choked. The straw is carried by the upper open belt, and is delivered over its 60 upper end upon the separators. To facilitate the operation of this straw-belt, a fluted roller, G, is mounted on journals e, and is located over, but near the lower end of, the straw-belt. This fluted roller holds the straw down on the 65 belt, and thereby renders the operation of the latter effectual.

f, f', f², and f³ designate the pulleys which drive the gangs 1, 2, 3, and 4 of straw-separating rollers, respectively, each with increasing 70 speed, owing to their decreasing diameter. In the present instance the separating-rollers consist of disks g, provided on their rims with teeth or notches g'. They may, however, instead of being notched, consist of hexagonal-shaped 75 plates, or plates having any number of angular projections. These rollers are mounted on the shafts C, h', h², and h³ at intervals, and in number sufficient to extend across the machine and constitute the gangs 1, 2, 3, and 4, 80 before referred to.

The separating-rakes I are each provided on their upper face with teeth or notches i, and at their lower end with a downwardly-projecting head, k, which part is mounted on the crank-shaft C, as seen in Figs. 2 and 3, one of these rakes being arranged between each two rollers, g. The rollers of the gang 1 are secured to the crank-shaft, but are concentric with the bearings of the said shaft. The highest or free 85 end of each separating-rake is provided on its lower side with a downward-slanting edge, l, which rests upon the shaft h³. By this arrangement, when the crank-shaft C rotates the lower ends of the separating-rakes have an up-and-down motion and the entire rake has an end-wise-reciprocating motion, while the highest or free end has a slight rising-and-falling motion as its downward-slanting edge l is drawn back and forth on the shaft h³. The effect of 90 this on the notched rakes is to lower them, draw them back, raise them, and then shove them 95

toward the rear or end where the straw has its exit. By this operation the straw is raised clear of the notched separating-rollers, shoved toward the rear, and then lowered on the rollers again. As there are four gangs of rollers, and each gang, from 1 to 4, is rotating at an increased rate of speed, it will be seen their action on the straw will be to pull it apart and open or loosen it on its passage to the end where it has exit. The conjoint action of the separating rollers and rakes is to so thoroughly loosen the straw that any grain which may remain mingled with the straw will be separated and fall between the rakes and rollers onto the incline *m*, by which it is directed into the winnowing-shoe.

Below the concave and the lower end of the straw-belt is an incline, *n*, onto which falls part of the grain and chaff from the thrashing-cylinder. This incline directs the grain and chaff onto the open grain-belt, which is carried over the shafts *E E'*. This grain-belt receives all the grain which is directed onto it by the incline *n*, and also all which is separated from the straw and passes through the slots *d* in the inclined bottom of the straw-belt. The grain-belt is constructed like the straw-belt—namely, with two belts, *a'*, cross-bars *b'*, and an inclined bottom, *c'*, which latter is without slots of any kind. This grain-belt conveys the grain and chaff to its upper end, just below which is an inclined board, *p*, onto which the grain and chaff fall, and by which they are directed into the winnowing-shoe *L*, which is provided with screens. (Not shown.)

The shaft *F* carries the blower, the air-blast from which drives the chaff out the rear exit. The operation of each of the several parts separately has already been indicated, but, considering them in proper sequence, may be stated as follows: The unthrashed straw and grain are passed below the cylinder and between it and the concave. The grain and chaff which are separated from the straw by this operation are delivered onto the grated bottom of the open

straw-belt, and most of them passes through the slots of the grate and is delivered onto the open grain-belt below. Inasmuch as the cross-bars of the straw-belt are continually passing over the grate or slots, they serve to keep them clear or open, and the grain is thereby allowed to separate itself at once from the straw. The straw, with such grain as may not have been separated from it, is carried to the separators, where, by the joint action of the separating rakes and rollers, heretofore explained, the strands of straw are so completely pulled apart and loosened that all the grain which may have remained mingled with the straw is separated and passed below, while the straw passes out the rear exit. While this operation is going on with the straw the grain which was separated and dropped through the slots is carried by the grain-belt to the winnower, where it meets such grain as may have passed with the straw to the separators.

The straw-belt with a bottom having slots, the straw-belt to carry the straw combined with a grain-belt to carry the grain, and the separating-rakes combined with the separating-rollers, may be used alone or separately from each other, or together in one machine, as in the present case.

Having described my invention, I claim and desire to secure by Letters Patent of the United States—

In a thrashing-machine, the combination of a crank-shaft, separating-rakes, each having one end mounted on said crank-shaft, and rollers, mounted also on the crank-shaft, but concentric with the bearings of said shaft, the rakes and rollers being placed alternately, as set forth.

In testimony whereof I affix my signature in presence of two witnesses.

HUGH W. MATTHEWS.
